UNITED STATES PATENT OFFICE.

LOUIS E. SCHOELKOPE, OF MADISON, WISCONSIN.

DOOR-OPERATING DEVICE.

Application filed July 5, 1927. Serial No. 203,404.

This invention relates to improvements in door operating devices.

It is one of the objects of the present invention to provide a door operating device having a remote control which may be easily operated to open and close sliding doors.

A further object of the invention is to provide a sliding door operating device which is actuated pneumatically and mechanically, and controlled electrically from one or more remote points.

A further object of the invention is to provide a sliding door operating device in which approximately one-half of the door opening or closing operation is actuated by means of compressed air, while the remaining half of the operation is actuated by a spring means which is initially put under tension by the compressed air.

20 A further object of the invention is to provide a sliding door operating device which, while operating to open or close the door automatically, does not prevent the manual opening or closing of the door when desired.

25 A further object of the invention is to provide a sliding door operating device with an air check which may be easily adjusted to cushion the opening and closing of the doors and to prevent slamming thereof.

30 A further object of the invention is to provide a door operating device which may be used for other purposes than for opening and closing doors.

35 A further object of the invention is to provide a door operating device in which the air control mechanism, electromagnets, etc., are mounted upon portions of the frame of the machine.

40 A further object of the invention is to provide a door operating device which is of simple construction, is strong and durable and is well adapted for the purpose described.

45 With the above and other objects in view the invention consists of the improved door operating device and its parts and combinations as set forth in the claims, and all equivalents thereof.

50 In the accompanying drawings in which the same reference characters indicate the same parts in all of the views:

Fig. 1 is an inside view of a sliding door and frame to which the improved door operating device is connected, the door being shown in full line in closed position and

partly open position in dotted line, the view also showing in diagrammatic form the circuit connection to the battery and the remote control switch;

60 Fig. 2 is a longitudinal sectional view of the main portion of the device;

Fig. 3 is an outside view of the main portion of the device taken at right angles to Fig. 2;

65 Fig. 4 is a sectional detail view of the attaching portions of the device and connected parts;

Fig. 5 is a detail view partly in section;

Fig. 6 is a transverse sectional detail view 70 taken on line 6—6 of Fig. 4;

Fig. 7 is a longitudinal sectional detail view of the outer end portion of the air cylinder on a slightly larger scale;

Fig. 8 is a similar view taken at right 75 angles to Fig. 7; and

Fig. 9 is a transverse sectional view taken on line 9—9 of Fig. 3 and on a larger scale.

Referring to the drawings, the numeral 10 indicates a door frame having a sliding door 80

11 suspended from a track 12 mounted on the frame, of ordinary construction. The improved door operating device comprises an angular bracket or main frame 13 having bolt openings 13' for attaching it to the 85 door frame or ceiling and is provided with a two part arm 14 which is pivotally connected at its inner end to the bracket 13 by a pivotal member 15. The outer or lower end of the arm is pivotally connected to a 90 bracket member 16 which is rigidly secured to the door. The arm 14 is formed of an inner head 17 which surrounds the pivot member 15 and forms the pivotal connection therewith. Spaced guide rods 18 connect-

95 ed to the inner head 17 project downwardly therefrom and at their outer ends are connected to an outer head 19. These rods are equidistantly spaced transversely and medially of their length are reinforced by a 100 two-part collar 20 which is formed with inner recesses 20' to receive and maintain said rods in position. The two parts of the collar are secured together by bolts and nuts 21. A closed inner end cylinder 22 is 105 positioned between the rods 18 and is provided with an outer cap 23. Said cap is of such diameter that it will be maintained in position and freely slide between the guide rods 18. A coiled spring 25 enclosed 110 by the guide rods 18 and surrounding the cylinder 22 is interposed between the cylin-

der cap 23 and an adjustable collar 26 slidably mounted on the rods 18. Two of the rods 18 are threaded, and nuts 27 mounted on the threaded portions and bearing against the inner side of the collar 26 adjustably hold the collar in position and the spring under the desired tension. As the outer end of the spring bears against the cylinder cap 23, it will hold the cylinder yieldingly in its outer position and bearing against the outer head 19. A piston 28 within the cylinder 22 is provided with a tubular stem 29 which extends through the cap of the cylinder and is threaded through the head 19. A jam nut 31 threaded on the outer portion of the stem 29 locks the stem to the head. The outer end of the tubular stem is connected to one end portion of an air valve casing 32 which is provided with a needle valve 33 for controlling the flow of air through said casing. The valve casing 32 is provided with a ball check valve 34 positioned to prevent the outward flow of air from the casing but permitting the ingress of air thereto from the tube 49. An exhaust valve 35 is threaded into the casing 32 and held in adjusted position by a coiled spring 36 for restricting the exhaust of air through the valve-groove opening 37 formed in the side portion of the screw valve 37 of the valve casing 32.

Tubular rods 38 threaded into the cylinder cap 23 extend loosely through the outer head 19 and at their outer ends are connected to a transverse bar 39 which is pivotally connected to the bracket member 16 mounted on the door 11 and form the outer arm part of the two part arm.

The angular bracket 13 is formed with a bore or tubular portion 40 to which is connected an air supply pipe 41 controlled by a hand valve 42. The pivotal member 15 is of tubular form and its bore 43 is in communication with the bore 40 and has a ball valve 44 seated therein which opens outwardly against the tension of a spring 45. The outer end of the spring bears against a trip lever 46 which is pivotally connected to the inner head 17. The pivotal member 15 is also provided with a sleeve 47 which adjustably threads into the bore of said member and forms an outer seat for the ball valve 44 to prevent the escape of air when the valve is in open position. A transversely extending duct 48 is located between the two valve seats to receive air under pressure when the valve is in open position. A tube 49 is connected to the inner head and is in communication with the duct 48 and extends therefrom alongside of the arm 14 and at its lower end is connected to the valve casing 32 adjacent the check valve 34. The inner head 17 is provided with an outwardly and downwardly extending arm 50 having an electromagnet 51 connected to its lower end

portion. The spring armature 52 of the magnet is formed with a shoulder 53 which is engaged by the lower end portion 46' of the trip lever 46 so that when the magnet is energized the armature 52 is swung downwardly to release the lower end of the trip lever and the compressed air and the valve spring 45 will force said lever outwardly. When the current to the magnet is opened or shut off the spring portion 52' of the armature will swing the armature outwardly and the inward or upward movement of the cylinder 22 in opening or closing the door will engage and move upwardly the depending trip lever rod 54 which is pivotally connected to the short inner end of the trip lever 46. When the trip lever is in open position the said rod 54 will be moved downwardly into the path of movement of the cylinder 22 and be returned to its normal upper position thereby. An oil duct 55 closed by a screw 56 provides for lubricating the pivotal member 15 and a pin 57 extending through the pivotal member and into the bracket 13 maintains the pivot pin 57 and its air duct in proper relation to the other parts.

To retard the outward swing of the trip lever 46 and to prevent rebound the screw or bolt 58, which forms the pivotal connection between the trip lever 46 and the inner head 17, is threaded through the inner head portion 17' of the head 17 and extends loosely through the bifurcated ends of the trip lever 46 and is provided with a nut and lock washer 59 for holding the bolts in adjusted position with relation to the trip lever. As the bolt is locked to the trip lever and the lever in swinging outwardly to open position will turn the bolt in the head portion 17' the side portion of the lever will be moved laterally and closer against the side of the head portion 17' and gradually check and stop said outward swing. In moving inwardly to armature engaging position, the thread will cause the lever to move away from the side portion of the inner head and be free to swing inwardly and engage the armature shoulder 53. By adjusting the bolt 58 to position the trip lever nearer to or further from the side portion of the frame, the trip lever may be retarded and stopped at any desired point. The electric circuit wires 60 extend to any desired point and include in their circuit a remote control switch 61 and an electric battery 62 for controlling the energization of the magnet. A guard spring 63 is attached to the magnet and extends over the free end of the armature to serve as a guard and stop for the armature.

In operation and with the parts in the position shown in full line in Figs. 1 and 2, the momentary closing of the switch 61 will cause the magnet to be energized and

draw down its armature and release the trip lever. This release will permit the spring 45 to force the lever outwardly and the pressure of the air from the supply pipe 5 will move the ball valve 44 to open position against the outer valve seat 43. The air under pressure will now be free to flow through the duct 48, the tube 49, the valve casing 32', move the check valve 34 to close 10 the exhaust valve 35 and through the casing 32 and the tubular piston stem 39 into the cylinder 22 between the piston and the upper end of the cylinder and move the cylinder upwardly. In moving upwardly, the 15 rods 38 connected to the cylinder and the door will slide the door to approximately half open position and the cylinder to a vertical position, as shown in dotted lines in Fig. 1. This upward movement of the cylinder will compress the spring 25 and move the trip lever rod 54 upwardly to return the trip lever 46 to its inner normal armature engaging position of rest. As thus moved 20 the ball valve 44 will be returned to its inner seat and close off the supply of compressed air to the cylinder and the valve 34 will then drop to its lower position as shown, and the air in the cylinder can then slowly exhaust through the valve groove 37 in the 25 valve 35. The door, in moving to approximately half open position, will acquire a certain inertia or momentum, and move the cylinder and the connected parts over the dead center line indicated in dotted lines in 30 Fig. 1. As soon as the parts swing over the dead center line, the compressed spring 25 will force the cylinder outwardly and slide the door to full open position where it will remain until the switch is again operated. 35 The cylinder in moving outwardly will force the air through the pipes and ducts before mentioned. To close the door, the switch is closed in the same manner, and the electromagnet will be again energized to release 40 the trip lever. This movement will admit air under pressure to the cylinder, and the movement of the cylinder will close the door approximately half way, and momentum and the spring 25 will complete the movement 45 in the same manner as before described. The outward movement of the cylinder will be checked somewhat by the adjustments of the valves 33 and 35 to restrict the flow of the air through the ducts controlled thereby. In moving the door manually, the check valve 34 permits the free entrance of air to the cylinder when said cylinder is moved inwardly.

From the foregoing description, it will 50 be seen that the fluid pressure is utilized to slide the door from a closed or open position to a half open or closed position, and in either instance the spring means is used to complete the movement in either direction.

55 For the work performed, the device is of

simple construction and is well adapted for the purpose described.

What I claim as my invention is:

1. The combination with a sliding door and its frame, of a means for opening and closing said door, comprising a bracket member connected to the frame, a two part arm pivotally connected to the bracket and to the door, the two portions of the arm slidably engaging each other, pneumatic means for moving one portion of the arm in one direction to slide the door a partial movement towards open or closed position, and a yielding means for moving the said arm portion in the opposite direction to complete the movement of the door towards open or closed position.

2. The combination with a sliding door and its frame, of a means for opening and closing said door, comprising a bracket member connected to the frame, a two part arm pivotally connected to the bracket and to the door, the two portions of the arm slidably engaging each other, pneumatic means for moving the outer portion of the arm inwardly for sliding the door a partial movement towards open or closed position, and a yielding means for moving the outer portion of the arm outwardly for completing the sliding movement of the door towards open or closed position.

3. The combination with a sliding door and its frame, of a means for opening and closing said door, comprising a bracket member connected to the frame, a two part arm pivotally connected to the bracket and to the door, the two portions of the arm slidably engaging each other, pneumatic means for moving one portion of the arm in one direction to slide the door a partial movement towards open or closed position, a yielding means for moving the said arm portion in the opposite direction to complete the movement of the door towards open or closed position, and a remotely positioned switch for electrically controlling the pneumatic means.

4. The combination with a sliding door and its frame, of a means for opening and closing said door, comprising a bracket member connected to the frame, a two part arm pivotally connected to the bracket and to the door, the two portions of the arm slidably engaging each other, pneumatic means for moving the outer portion of the arm inwardly for sliding the door a partial movement towards open or closed position, a yielding means for moving the outer portion of the arm outwardly for completing the sliding movement of the door towards open or closed position, and a remotely positioned switch for electrically controlling the pneumatic means.

5. The combination with a sliding door and its frame, of a means for opening and

closing said door, comprising a bracket member connected to the frame, an inner arm part pivotally connected to the arm, an outer arm part pivotally connected to the door, a cylinder connected to the outer arm part and slidably engaged by the inner arm part, a piston within the cylinder and having a stem which is connected to the inner arm part, means for supplying air under pressure to the cylinder to move it inwardly, other means for moving the cylinder outwardly, and an electrical means for controlling the admission of air to the cylinder.

15 6. The combination with a sliding door and its frame, of a means for opening and closing said door, comprising a bracket member connected to the frame, an inner arm part pivotally connected to the arm, an outer arm part pivotally connected to the door, a cylinder connected to the outer arm part and slidably engaged by the inner arm part, a piston within the cylinder and having a stem which is connected to the inner arm part, means for supplying air under pressure to the cylinder to move it inwardly, a spring means placed under tension by the pressure of the air in the cylinder for moving the cylinder outwardly, and an electrical means carried by the inner arm and remotely controlled for controlling the admission of air to the cylinder.

7. The combination with a sliding door and its frame, of a means for opening and closing said door, comprising a bracket member connected to the frame, an inner arm part pivotally connected to the arm, an outer arm part pivotally connected to the door, a cylinder connected to the outer arm part and slidably engaged by the inner arm part, a piston within the cylinder and having a stem which is connected to the inner arm part, means for supplying air under pressure to the cylinder to move it inwardly, a coiled spring surrounding the cylinder and placed under tension by the pressure of air in the cylinder for moving the cylinder outwardly, and an electrical means remotely controlled for controlling the admission of air to the cylinder.

8. The combination with a sliding door and its frame, of a means for opening and closing said door, comprising a bracket member connected to the frame, an inner arm part pivotally connected to the arm and having a valve, a trip lever pivotally connected to the arm part for actuating the valve, an outer arm part pivotally connected to the sliding door, a cylinder connected to the outer arm part and slidably engaging the inner arm part, a piston within the cylinder and having a stem which is connected to the outer end of the inner arm part, means for supplying air under pressure to the cylinder to move it inwardly, said air be-

ing controlled by the valve, a trip lever pivotally connected to the inner arm part and engaging the valve, a coiled spring interposed between the inner and the outer arm parts for moving the outer arm part outwardly, and a remotely controlled electromagnet carried by the inner arm part for controlling the trip lever.

9. The combination with a sliding door and its frame, of a means for opening and closing said door, comprising a bracket member connected to the frame, an inner arm part pivotally connected to the arm and having a valve, a trip lever pivotally connected to the arm part for actuating the valve, an outer arm part pivotally connected to the sliding door, a cylinder connected to the outer arm part and slidably engaging the inner arm part, a piston within the cylinder and having a stem which is connected to the outer end of the inner arm part, means for supplying air under pressure to the cylinder to move it inwardly, said air being controlled by the valve, a trip lever pivotally connected to the inner arm part and engaging the valve, a coiled spring surrounding the cylinder and interposed between the inner and the outer arm parts for moving the outer arm part outwardly, an electromagnet carried by the inner arm part and engaging the trip lever to hold the valve in closed position, an electric circuit which includes the electromagnet, and a remotely positioned switch included in the electric circuit for controlling the current to the magnet.

10. The combination with a sliding door and its frame, of a means for opening and closing said door, comprising a bracket member connected to the frame and having a tubular pivot member having a valve seat and a valve therein, an air supply pipe in communication with the pivot member, an inner arm member having a head which is pivotally mounted on the pivot member and also having a port in register with the bore of the pivot member, a coiled spring engaging the valve and projecting out of the bore of the pivot member, a trip lever pivotally connected to the head and engaging the spring, an electromagnet connected to the head and having an armature which holds the trip lever and the valve in closed position, an outer arm part pivotally connected to the sliding door, a cylinder connected to the outer arm and slidably engaging the inner arm part, a piston within the cylinder and having a tubular stem which is connected to the outer end of the inner arm part, a check valve casing connected to the outer end of the piston stem and having an inwardly opening check valve, a needle valve controlling the flow of air through said valve casing, a tube connected to said valve casing and to the port of the inner head, a valve controlling the

flow of air from the tube to the valve casing, an electric circuit in which the electromagnet is included, and a remotely positioned switch included in the electric circuit 5 for controlling the electromagnet.

11. The combination with a sliding door and its frame, of a means for opening and closing said door, comprising a combined pneumatic and spring means for sliding the 10 door from one position to another, the pneumatic means initially sliding the door for approximately one-half portion of its movement and the spring means completing the movement, and an electromagnet means for 15 controlling the operation of the parts.

12. The combination with a sliding door and its frame, of a means for opening and closing said door, comprising a combined pneumatic and spring means for sliding the 20 door from one position to another, the pneumatic means initially sliding the door for approximately one-half portion of its movement and at the same time compressing the spring means and the spring means 25 completing the movement in either direction, and an electromagnetic means for controlling the operation of the parts.

13. The combination with a sliding door and its frame, of a means for opening and 30 closing said door, comprising a bracket member connected to the frame, an inner arm part pivotally connected to the bracket and having a valve, a trip lever pivotally connected to the arm part for actuating the 35 valve, an outer arm part pivotally connected to the sliding door, a cylinder connected to the outer arm part and slidably engaging the inner arm part, a piston within the cylinder and having a stem which is connected 40 to the outer end of the inner arm part, means for supplying air under pressure to the cylinder to move it inwardly, said air being controlled by the valve, a trip lever pivotally connected to the inner arm part 45 and engaging the valve and movable outwardly to permit the valve to move to open position, means for automatically moving the trip lever inwardly, a coiled spring interposed between the inner and the outer arm 50 parts for moving the outer arm part outwardly, and a remotely controlled electromagnet carried by the inner arm part for controlling the trip lever.

14. The combination with a sliding door and its frame, of a means for opening and closing said door, comprising a bracket mem-

ber connected to the frame, an inner arm part pivotally connected to the arm and having a valve, a trip lever pivotally connected to the arm part for actuating the 60 valve, an outer arm part pivotally connected to the sliding door, a cylinder connected to the outer arm part and slidably engaging the inner arm part, a piston within the cylinder and having a stem which is connected 65 to the outer end of the inner arm part, means for supplying air under pressure to the cylinder to move it inwardly, said air being controlled by the valve, a trip lever pivotally connected to the inner arm part and 70 engaging the valve and movable outwardly to permit the valve to move to open position, means engaged by the inward movement of the cylinder for automatically moving the trip lever to its inner position, a coiled 75 spring interposed between the inner and the outer arm parts for moving the outer arm part outwardly, and a remotely controlled electromagnet carried by the inner arm part for controlling the trip lever. 80

15. The combination with a sliding door and its frame, of a means for opening and closing said door, comprising a bracket member connected to the frame, an inner arm part pivotally connected to the arm and 85 having a valve, a trip lever pivotally connected to the arm part for actuating the valve, an outer arm part pivotally connected to the sliding door, a cylinder connected to the outer arm part and slidably engaging 90 the inner arm part, a piston within the cylinder and having a stem which is connected to the outer end of the inner arm part, means for supplying air under pressure to the cylinder to move it inwardly, said air being 95 controlled by the valve, a trip lever pivotally connected to the inner arm part and engaging the valve and movable outwardly to permit the valve to move to open position, adjustable means for limiting the outward 100 movement of the trip lever, a rod engaged by the inward movement of the cylinder for automatically moving the trip lever to its inner position, a coiled spring interposed 105 between the inner and the outer arm parts for moving the outer arm part outwardly, and a remotely controlled electromagnet carried by the inner arm part for controlling the trip lever.

In testimony whereof, I affix my signature. 110

LOUIS F. SCHOELKOPF.
